DESIGN FOR A SWITCH AND FUSE LOCK

David Conlan, New York, N. Y., assignor to
Conlan Electric Corporation, New York, N. Y.

Application December 6, 1944, Serial No. 116,753

Term of patent 14 years

(Cl. D26—1)

To all whom it may concern:

Be it known that I, David Conlan, a citizen of the United States, residing at New York, in the county and State of New York, have invented a new, original, and ornamental Design for a Switch and Fuse Lock, of which the following is a specification, reference being had to the accompanying drawing forming part thereof.

Fig. 1 is a perspective view of a switch and fuse lock embodying my new design; and
Fig. 2 is a front view of the same.

I claim:

The ornamental design for a switch and fuse lock, substantially as shown.

DAVID CONLAN.
